UNITED STATES PATENT OFFICE.

JAMES MONTGOMERY, OF NEW YORK, N. Y., ASSIGNOR TO WALLACE & CO., OF BROOKLYN, NEW YORK, A CORPORATION OF NEW JERSEY.

DESIGN FOR A BOX.

Application filed December 19, 1924. Serial No. 11,753. Term of patent 7 years.

To all whom it may concern:

Be it known that I, JAMES MONTGOMERY, a citizen of the United States of America, residing at New York city, county and State of New York, have invented a new, original, and ornamental Design for a Box, of which the following is a specification, reference being had to the accompanying drawing, forming a part thereof.

In the drawing—

The drawing is a perspective view of a box showing my design.

I claim:—

The ornamental design for a box substantially as shown.

JAMES MONTGOMERY.
